LAUNDRY PRESSING MACHINE

Leo M. Kahn and Frank J. Kahn, New York,
N. Y.; said Frank J. Kahn assignor to said
Leo M. Kahn

Application December 23, 1936, Serial No. 117,312

28 Claims.

(Cl. 38—22)

This invention relates to improvements in pressing machines of the type generally used in laundries and particularly to a pressing machine having superimposed independent upper and lower ironing units which may be successively utilized by one operator.

An object of this invention is to provide a pressing machine having upper and lower ironing units, comprising a substantially fixed upper ironing element, a movable lower ironing element, a coacting duplex intermediate element and means for causing the lower element to be raised to a predetermined operating position when the intermediate element is raised into ironing position.

Another object of this invention is to provide means for locking the intermediate element in the upper or lower ironing positions, and means for producing an ironing pressure selectively in said upper and lower ironing units when in said locked positions.

Another object of this invention is to provide a pressing machine having upper and lower ironing units in vertically spaced relation and comprising vertically reciprocable actuating mechanism contained in a single frame to thereby conserve floor space and save the time and energy of the operator.

Another object of this invention is to provide a pressing machine having upper and lower independent ironing units, a movable duplex intermediate ironing element, and a lower ironing element, which may be moved to predetermined operating position when the intermediate duplex element is raised into coacting ironing position with the upper ironing element.

Another object of this invention is to provide a pressing machine having upper and lower ironing units, comprising an upper ironing element having a steam chest in which steam is confined, a duplex intermediate ironing element having a steam chest as its lower face and a work supporting surface as its upper face, and a lower work supporting ironing element.

With the above and other objects in view, the invention will be hereinafter more particularly described and the combination and arrangement of parts will be shown in the accompanying drawings and pointed out in the claims which form part of the specification.

Reference will now be had to the drawings wherein like numerals of reference designate corresponding parts throughout the several views, in which:

Figure 1 is an end elevation of the pressing machine.

Figure 2 is a front elevation partly in section, the section being taken as on line 2—2 in Figure 1.

Figure 3 is a fragmentary cross-sectional view, the section being taken as on line 3—3 in Figure 2.

Figure 4 is an end view of the combination or duplex buck.

Figure 5 is an end view of a modified pressing machine having upper and lower ironing units positioned in separate vertical planes, and having a duplex intermediate ironing member movable horizontally between said ironing units.

Figure 6 is an end view of a modified pressing machine having upper and lower ironing units positioned in angular relation, and having a duplex intermediate ironing member pivotally mounted for swinging motion between said ironing units.

Figure 7 is an end view of a modified pressing machine of the jaw type, having upper and lower ironing units positioned in angular relation, and having a duplex intermediate ironing member pivotally mounted and held centrally for swinging motion between said ironing units.

Figure 8 is a front elevation of the embodiment of the invention shown in Figure 5.

In the illustrated embodiment of the invention shown in Figures 1 to 4 inclusive, the several views show a pressing machine of the type generally used in laundries and comprising a frame 10 having uprights 11, 11, provided with extension ribs 11' to receive tie rods 12, said uprights being affixed at their lower ends to a cross-member 13, as for example by bolts, not shown, or by welding. The lower cross-member 13 preferably comprises bifurcated uprights 14 providing a central opening therebetween (not shown) designed to permit upright motion of a cross-bar 16.

The ends of the cross-bar 16 have apertured bosses 17 designed to receive tubular uprights 18, 18 which may be fixed to the bosses by pins 19. The tubular uprights 18 are supported adjacent to their upper ends in bearings 20 at the upper elevation of the uprights 11, and at their lower ends in bearings 21 in the base portions 22 of the frame.

Mounted on the upper portions of the tubular uprights 18 is a heated ironing element 23 having apertured bosses 24, through which the said uprights pass and pins 25 may be used to fasten the ironing element 23 to the uprights 18 with the ironing surface 26 in horizontally disposed

position. Open coil springs 27 resting on the bearings 20 support the ironing element 23 in a resilient manner. A toggle joint 28 having arms 29, 29 hinged at 30 and pivotally mounted on pivots 31 and 32, is operatively connected to a cylinder 33. The cylinder 33 may be secured to the cross-member 13 on a pivot 34.

Motive fluid is supplied to the cylinder 33 through an inlet conduit 35. An outlet conduit 36 is provided for exhaust fluid. It is thus possible by admitting motive fluid to the cylinder 33 to actuate the piston rod 37 and the toggle 28 and cause a slight lowering of the bar 16 and the ironing member 23 against the resilient action of the springs 27 for a purpose which will appear later in this specification.

A buck 40 having an upper work supporting surface 41' and a lower horizontal plate 41 rests upon the upper surface of the cross-member 13. The ends 42 of the plate 41 extend beyond and overhang the uprights 14. The plate 41 has centrally positioned end openings 43 which engage the tubular uprights 18 in slidable relation.

Mounted centrally of the uprights 11, are cylinders 45, having piston rods 46 operatively positioned therein. Extension arms 47, secured at the upper end of the piston rods 46, are designed to support a combination or duplex buck 48. The buck 48 comprises an upper work supporting ironing surface 49 and a lower heated ironing surface 50 which are positioned in spaced horizontal relation. The lower ironing surface 50 may comprise the face of a steam-chest heated in the usual manner and the upper work-supporting ironing surface 49 may be padded in the usual manner and adapted for the reception of work to be ironed. The steam-chest of which the surface 50 is a part is preferably separated from the work-receiving surface 49 by a neck or other narrow support, thus providing in the element 48 an undercut portion between the work-receiving surface 49 and the heated ironing surface 50 for the reception of work overhanging from the surface 49. Such a structure is readily adapted to the handling of large pieces without having the overhang come in contact with the lower ironing surface 50. Motive fluid is supplied to the cylinders 45, best shown in Fig. 1, through an inlet conduit 51 and an outlet conduit 52 is provided for the exhaust fluid. The inlet and outlet conduits pass through a self-closing fluid pressure supply valve 53 having a motive fluid supply conduit at 54. The valve 53 has a spring-pressed push button 55 for admitting the motive fluid from the conduit 54.

It may be found desirable to raise the lower buck 40 to a higher loading position than that shown in Fig. 2. For this purpose, there are provided arms 67, attached to the extension arms 47. The arms 67 have angularly bent extensions 68 provided with vertically adjustable threaded members 69. When the buck 48 is caused to rise vertically, the buck 40 will be lifted by the threaded member 69 to a height determined by the position of the members 69.

It is to be noted that the duplex buck 48 is shown as built in two sections fastened together by bolts 40' which may be removed so as to permit the substitution of a section of different shape or size for the work receiving element of the duplex buck. It is obvious that the upper ironing element 23 would then have to conform. It is to be noted that instead of the duplex buck 48 having upper and lower ironing surfaces, 75 which move as a unit, these upper and lower in-

termediate ironing surfaces may be separately and independently movable and still coact to accomplish the purposes of the present invention.

The operation of the pressing machine is as follows:

Assume the elements of the device are in the position shown in solid lines in Figures 1 and 2. Damp work to be ironed is placed on the upper surface 49 of the buck 48 and when laid properly, the operator momentarily presses control handles 56 downwardly part way, and lowers the rods 58 which are held upwardly by spring 58' thereby actuating the angular levers 59 against the springs 60 and releasing the locking members 57. It is to be understood that while Fig. 2 shows the mechanism now being described at only one side of the device, for clarity, it is preferably duplicated at the other side of the machine so that locking members 57 which may be provided at either side of the member 48 may be simultaneously released.

The operator then presses the push button 55 of the valve 53 to admit motive fluid into the cylinders 45 to cause the buck 48 to move upwardly against the heated ironing element 23 as best shown in dot-and-dash lines in Figure 2. As the buck 48 rises into its upper position the locking members 57 pivotally mounted at 47' on the buck extension arms 47 of the buck 48 are pressed into engagement with the lugs 61 in the frame 11 by leaf-springs 62. Similar lugs 61' on the tubular uprights 18 and leaf springs 62' are shown in the low position. Similar angular levers 59 in the low position are simultaneously operated by the rods 58. In the upper position, the buck 48 contacts a plunger 63 of an inlet valve 73 having an inlet conduit 63' and which valve may be of any standard type. The movement of the plunger 63 causes motive fluid to pass through the conduit 35 to actuate piston 27 and the toggle 28, thus pushing the bar 16 and the tubular uprights 18 downwardly and lowering the heated ironing element 23 so as to cause heavy ironing pressure against the work placed on the surface 49 of the buck 48 which is locked against downward movement by the engagement of the elements 57 with the notches 61.

As it requires from 20 to 30 seconds to dry and iron an average damp article, it is an object of this invention to utilize this waiting time of the operator to place another damp article on the buck 40. The buck 40 is made accessible by moving the intermediate buck 48 to the upper position shown by the dot-and-dash lines. When the damp article has been properly placed on the lower buck 40 and the operator is ready for same to be ironed, the buck 48 having the heated ironing surface 50, is brought downward through the action of the operator in depressing the control levers 56 to the extreme downward position so as to move the plungers 53' and 36' of the valves 53 and 74, thus exhausting the motive fluid from the cylinders 45 and 33. Plunger 36' is moved at once and slightly before plunger 53' by the downward movement of a rod 64 attached at 65 to the rod 58 (see Fig. 1), exhausting the motive fluid pressure in cylinder 33 and releasing the pressure against the buck 48, making it easier for the operator to move the locking members 57 out of holding position. When the intermediate element drops to the lower ironing position, pressure is exerted by the surface 50 against the surface 41' in the following manner. The element 48 contacts a plunger 63 on a valve 73 suitably positioned as shown in Fig. 1 and 75

operative in the manner heretofore described in connection with the description of the upper valve and plunger similarly numbered, to build up fluid pressure in the cylinder 33 and through 5 the toggle 28 to force down against the element 40 the element 48, which is locked with respect to the elements 18 by the elements 57 which bear against the notches 61 in the elements 18.

It will thus be seen that the novelty of the 10 invention resides in a combination or duplex buck which serves a double purpose and allows for the saving of floor space due to its vertical movement into two service positions. By contacting its upper supporting surfaces 49 with the 15 heated ironing surface of the upper ironing element 23 and thereby giving access to the work supporting surface of the lower buck and by contacting its lower ironing surface 50 with the buck 40 when brought into the low position, the operator 20 is constantly occupied in getting work ready to be ironed.

As shown in Figures 5 and 8, there has been provided a modified pressing machine 100 having an upper ironing element 101 and a lower 25 ironing element 102 which are positioned in separate vertical planes. A duplex intermediate ironing member 103 having an upper ironing surface 104 and a lower ironing surface 105 has been mounted on extensions 106 which are 30 designed to move horizontally in guide slots 107 between the ironing elements 101 and 102.

An arm 108 pivotally mounted on a pivot 109 and actuated by a motive fluid member 110 may serve to cause the horizontal reciprocating 35 motions of the duplex ironing member 103.

Means to provide pressure between adjacent ironing surfaces is shown in Fig. 8. Cylinders 150 and 151 mounted above the head 101 and below the buck 102 may be connected to rotary 40 cams 152 and 153 so that by admission of air to either cylinder either cam may be rotated and pressure applied to either pair of contiguous surfaces.

It will be readily seen that the modified pressing machine functions to provide an upper ironing unit 111 and a lower ironing unit 112 which are independent of each other.

As shown in Figure 6, there has been provided a modified pressing machine 115 having an upper ironing element 116 and a lower ironing element 117 positioned in angular relation. A duplex intermediate ironing member 118 having an upper ironing surface 119 and a lower ironing surface 120 has been mounted for swinging 55 motion on arms 121 between the ironing elements 116 and 117. The arms 121 are respectively positioned at opposite sides of the member 118 and are pivotally mounted on a pivot 121' which may operate in angular slots 122 designed 60 to permit raising and lowering the member 118 against the upper and lower ironing elements 116 and 117 in order to apply a heavy ironing pressure in the upper ironing unit 123 and the lower ironing unit 124. A motive fluid member 65 125 may be used to cause the swinging motion of the member 118.

As shown in Figure 7, there has been provided a modified pressing machine of the jaw type 130, having an upper ironing element 131 and a lower 70 ironing element 132 positioned in obtuse angular relation.

A duplex intermediate ironing member 133 having an upper ironing surface 134 and a lower ironing surface 135 has been pivotally mounted 75 for swinging motion on an arm 137 and a pivot

136. A motive fluid member 138 may be employed to actuate a toggle 139 and raise and lower an arm 140 which brings the duplex member 133 into coaxing relation with the upper and lower ironing surfaces 131 and 132. 5

It is to be noted that in all the embodiments herewith shown, the duplex intermediate member which forms one of the main features of this invention, has a steam chest where steam is confined under pressure in its lower ironing surface, 10 and that the stationary upper steam chest likewise serves to confine the steam under pressure for ironing purposes which forms part of the upper ironing unit.

Having thus described several embodiments of 15 our invention, what we claim is:

1. In a pressing machine, in combination, a buck member, a head member and an intermediate element comprising an upper buck portion and a lower pressing portion, means for so spacing said portions as to provide a recess therebetween for the reception of work, means for moving said intermediate element into engagement with said head member, means for exerting pressure between said element and said member, means for moving said intermediate element into pressing engagement with said buck member and for simultaneously moving the buck portion of said element to work-receiving position, and means for exerting pressure between 20 the pressing portion of said element and said buck member. 25

2. In a pressing machine, in combination, a buck member, a head member and an intermediate element comprising an upper buck portion and a lower pressing portion, means for so spacing said portions as to provide a recess therebetween for the reception of work, means for moving said intermediate element into engagement with said head member, means for locking said element and member together, 35 means for exerting pressure between said element and said member by moving said member against said element, means for moving said intermediate element into pressing engagement 40 with said buck member and for simultaneously moving the buck portion of said element to work-receiving position, and means for exerting pressure between the pressing portion of said element and said buck member. 45

3. In a pressing machine, in combination, a buck member, a head member and an intermediate element comprising an upper buck portion and a lower pressing portion, means for so spacing said portions as to provide a recess therebetween for the reception of the overhang of work, means for moving said intermediate element into engagement with said head member, means for exerting pressure between said element and said member, means for moving said intermediate element into pressing engagement with said buck member and for simultaneously moving the buck portion of said element to work-receiving position, and means for exerting pressure between the pressing portion of said element 55 and said buck member, all of said pressure-exerting means being separate from the means for moving said intermediate element. 60

4. In a pressing machine, in combination, a buck member, a head member and an intermediate element comprising a work-receiving upper buck portion and a lower pressing portion comprising a steam-chest, means for so spacing said portions as to provide a recess therebetween for the reception of work, means for moving said 70 75

- intermediate element into engagement with said head member, means for exerting pressure between said element and said member, means for moving said intermediate element into pressing engagement with said buck member and for simultaneously moving the buck portion of said element to work-receiving position, and means for exerting pressure between the pressing portion of said element and said buck member, said pressure-exerting means being controlled by mechanism automatically operative upon substantial engagement of said intermediate element with either one of said members.
5. In a pressing machine, in combination, a buck member, a head member and an intermediate element comprising an upper buck portion and a lower pressing portion, means for so spacing said portions as to provide a recess therebetween for the reception of work, means for moving said intermediate element into engagement with said head member, means for exerting pressure between said element and said member, means for moving said intermediate element into pressing engagement with said buck member and for simultaneously moving the buck portion of said element to work-receiving position, means for exerting pressure between the pressing portion of said element and said buck member, and means for releasing the pressure between said intermediate element and either of said members before motion of said element with respect to either of said members.
6. In a pressing machine, in combination, a head member, a buck member and an intermediate duplex element comprising spaced buck and head portions, means to move said buck member between an elevated work-receiving position and a lower pressing position, means to move said duplex element between an elevated 30 pressing position in contact with said head member and a lower work-receiving position in contact with said buck member, and means for exerting pressure between said head member and the buck portion of said duplex member, and between said buck member and the head portion of said duplex member.
7. In a pressing machine, in combination, a head member, a buck member and an intermediate duplex element comprising spaced buck and head portions, means to move said buck member between a work-receiving position and a pressing position, means to move said duplex element between a pressing position in contact with said head member and a work-receiving position in contact with said buck member, and means for exerting pressure between said head member and the buck portion of said duplex member, and between said buck member and the head portion of said duplex member.
8. In a pressing machine, in combination, a head member, a buck member and an intermediate duplex element comprising spaced buck and head portions, means to move said buck member between an elevated work-receiving position and a lower pressing position, means to move said duplex element between an elevated pressing position in contact with said head member and a lower work-receiving position in contact with said buck member, locking means for holding said duplex element in alternate locked engagement with each of said members, and means for exerting pressure between said head member and the buck portion of said duplex member, and between said buck member and the head portion of said duplex member.
9. In a pressing machine, in combination, a head member, a buck member and an intermediate duplex element comprising spaced buck and head portions, means responsive to motion of said duplex member to move said buck member between an elevated work-receiving position and a lower pressing position in contact with said head member and a lower work-receiving position in contact with said buck member, and means for exerting ironing pressure between said head member and the buck portion of said duplex member, and between said buck member and the head portion of said duplex member.
10. In a pressing machine, in combination, a head member, a buck member and an intermediate duplex element comprising spaced buck and head portions, means to move said buck member between a work-receiving position and a pressing position, means to move said duplex element between a pressing position in contact with said head member and a work-receiving position in contact with said buck member, means for exerting ironing pressure between said head member and the buck portion of said duplex member and between said buck member and the head portion of said duplex member, and means for automatically releasing said ironing pressure before the means for moving the duplex element becomes effective.
11. A press of the character described comprising frame elements, a pressing head yieldingly supported on said frame elements, a buck member spacially positioned with respect to said head, a duplex element comprising a work-supporting surface and a work-pressing surface spaced from each other by means providing a recess for work hanging from said work-supporting surface, guide means associated with said frame for guiding said duplex member from a position with its work-supporting surface in contact with said head to a position with its work-pressing surface in contact with said buck, means to move said duplex member along said guide means, locking means associated with said duplex member for holding said member in engagement with either said head or with said buck, means to force said head into pressing engagement with said duplex member after said duplex member has been locked with respect to said head, and means to effect a release of said pressure before said locking means is disengaged.
12. A press of the character described comprising frame elements, a pressing head yieldingly supported on said frame elements, a buck member spacially positioned with respect to said head, a duplex element comprising a work-supporting surface and a work-pressing surface spaced from each other by means providing a recess for work hanging from said work-supporting surface, guide means associated with said frame and cooperating with extensions from the work-pressing surface of said duplex element for guiding said duplex member from a position with its work-supporting surface in contact with said head to a position with its work-pressing surface in contact with said buck without substantial change in the angular position of the work-supporting surface of said duplex element, means to move said duplex member along said guide means, locking means associated with said duplex member for holding said member in engagement with either said head or with said buck, means to force said head into pressing engagement with said duplex member.

duplex member after said duplex member has been locked with respect to said head, and means to effect a release of said pressure before said locking means is disengaged.

5 13. A press comprising a head having a steam-chest therein, a buck having a padded work-receiving surface supported by a narrow neck, an intermediate element, supporting elements comprising guides on which said buck and head and intermediate elements are mounted, said intermediate element having a second steam-chest and extensions upon said second steam-chest slideable upon said guides, a neck upon said second steam-chest and a work-receiving surface supported by said neck, means for sliding said intermediate element from a position in contact with said buck to a position in contact with said head and means disconnected during said movement and engageable when the intermediate element comes into contact with the head or with the buck for exerting pressure between said intermediate element and said head or buck.

20 14. A press of the character described having a head member and a buck member spaced therefrom, an intermediate element movable therebetween, said element comprising a steam-chest and a narrow neck extending above said chest and supporting a work-receiving surface, means for raising said intermediate element from a loading position to a position in contact with said head, and means for raising said buck from a position in contact with the steam-chest of said intermediate element to a work-receiving position, said last-mentioned raising means being adapted to function after said intermediate element has moved from contact with said buck.

25 15. A press of the character described having a head member and a buck member spaced therefrom, an intermediate element movable therebetween, said element comprising a steam-chest and a narrow neck extending above said chest and supporting a work-receiving surface, means for raising said intermediate element from a loading position to a position in contact with said head, and means for raising said buck from a position in contact with the steam-chest of said intermediate element to a work-receiving position, said last-mentioned raising means being adapted to function after said intermediate element has moved from contact with said buck, and pressure-exerting means operative upon engagement by said intermediate element with said buck and with said head to exert ironing pressure between adjacent surfaces of said intermediate element and said buck and said head.

30 16. A press of the character described having a head member and a buck member spaced therefrom, an intermediate element movable therebetween, said element comprising a steam-chest and a narrow neck extending above said chest and supporting a work-receiving surface, means for raising said intermediate element from a loading position to a position in contact with said head, and means for raising said buck from a position in contact with the steam-chest of said intermediate element to a work-receiving position, said last-mentioned raising means being adapted to function after said intermediate element has moved from contact with said buck, and pressure-exerting means operative upon engagement by said intermediate element with said buck and with said head to exert ironing pressure between adjacent surfaces of said intermediate element and said buck and said head, and means for releasing said

35 pressure-exerting means prior to motion of said intermediate element.

17. A press of the character described comprising a head member and a buck member spaced from each other, an intermediate element movable between them having a steam-chest, a padded work-receiving surface carried by said steam-chest and spaced therefrom to provide an undercut portion, means connected to said steam-chest for moving said intermediate element between a position in contact with said head and a position in contact with said buck, and means operative during movement of the intermediate element for moving one of the other members away from its position of contact to facilitate loading.

40 18. A press of the character described having a head and buck spaced from each other, an intermediate element movable between them, said intermediate element having a steam-chest, a padded work-receiving surface supported in spaced relation above said steam-chest, means for moving said intermediate element between a position to engage said buck and a position to engage said head, means for raising said buck from its contact position with said intermediate element to a position for loading and means for coordinating said buck-moving means to operate during movement of said intermediate element.

45 19. A press comprising a movable buck and a movable head, another buck and another head, said movable head having lugs extending outwardly from its ends, a pair of vertical guides, said lugs being slideable on said guides, a neck carried by said movable head for spacing said movable buck therefrom, said movable buck being carried by said movable head, means for moving said movable head to bring said movable buck into engagement with said other head and to bring said movable head into engagement with said other buck, and means for automatically exerting pressure between the engaged elements upon engagement thereof.

50 20. A press comprising a movable head and a movable buck and another head and another buck, said movable head and buck being connected together to move as an intermediate element, a piston and cylinder for moving said intermediate element from a position in engagement with said other buck to a position in engagement with said other head, a piston and cylinder for pressing together said intermediate element and said head or buck upon engagement of said element therewith, manually controlled means for admitting fluid to said first-mentioned cylinder, and means automatically controlled by the position of said element for admitting fluid to said second-mentioned cylinder.

55 21. A press comprising a movable head and a movable buck and another head and another buck, said movable head and buck being connected together to move as an intermediate element, a piston and cylinder for moving said intermediate element from a position in engagement with said other buck to a position in engagement with said other head, a piston and cylinder for pressing together said intermediate element and said head or buck upon engagement of said element therewith, manually controlled means for admitting fluid to said first-mentioned cylinder, and means automatically controlled by the position of said element for admitting fluid to said second-mentioned cylinder, and means to move said other buck between a loading position and a pressing position.

22. A press comprising a movable head and a movable buck and another head and another buck, said movable head and buck being connected together to move as an intermediate element, a piston and cylinder for moving said intermediate element from a position in engagement with said other buck to a position in engagement with said other head, a piston and cylinder for pressing together said intermediate element and said head or buck upon engagement of said element therewith, manually controlled means for admitting fluid to said first-mentioned cylinder, means automatically controlled by the position of said element for admitting fluid to said second-mentioned cylinder, and means for releasing the fluid pressure in said second cylinder before altering the fluid pressure in said first cylinder.
23. A press comprising in combination a head member, a buck member and a movable intermediate element having a cut-out portion to receive the overhanging work, means for moving it from a position in contact with one member to a position in contact with the other, means actuated by the position of the intermediate element for locking it in position with respect to either of the other members when it is in contact therewith, means for thereupon exerting pressure between the intermediate element and the adjacent member, and common means for releasing the locking means and the pressure-exerting means and for actuating said moving means.
24. A press comprising in combination a head member, a buck member and a movable intermediate element having a cut-out portion to receive the overhanging work, means for moving it from a position in contact with one member to a position in contact with the other, means actuated by the position of the intermediate element for locking it in position with respect to either of the other members when it is in contact therewith, means for thereupon exerting pressure between the intermediate element and the adjacent member, common means for releasing the locking means and the pressure-exerting means and for actuating said moving means, means to move said buck member from a lower pressing position to an elevated loading position, and means to coordinate the motion of the buck member with the motion of the intermediate element.
25. In a pressing machine, in combination, work-supporting means, heated work-pressing means spaced from and positioned above said work-supporting means, further work-supporting means and heated work-pressing means positioned intermediate said first-mentioned work-supporting means and work-pressing means, means to space said second-mentioned work-supporting means from said second-mentioned work-pressing means so as to provide a recess therebetween for the reception of work, means for moving said second-mentioned work-supporting means between a position in pressing engagement with said first-mentioned work-pressing means and a work-receiving position spaced therefrom, means for moving said second-men-
- tioned work-pressing means from a position in pressing engagement with said first-mentioned work-supporting means and a position spaced therefrom, means to exert pressure between said first-mentioned pressing means and said second-mentioned work-supporting means, and means to exert pressure between said second-mentioned pressing means and said first-mentioned work-supporting means.
26. In a pressing machine, in combination, a buck member, a head member, means to position said head member above and spaced from said buck member, an intermediate element comprising an upper buck portion and a lower pressing portion, means for so spacing said portions as to provide a recess therebetween for the reception of work, means comprising motive fluid-actuated means for moving said intermediate element into pressing engagement with said head member, means for exerting pressure between said element and said member, means for moving said intermediate element into pressing engagement with said buck member and into a position so spaced from said head member that work may be readily placed upon the buck portion of said intermediate element, and means for exerting pressure between the pressing portion of said intermediate element and said buck member.
27. In a pressing machine, in combination, a buck member, a head member positioned above said buck member, intermediate buck and head members spaced from each other to provide a recess therebetween for the reception of work, means affixed to said intermediate head member and comprising a plurality of oppositely extending arms for moving said intermediate members between a pressing engagement with said head member and a pressing engagement with said buck member, means to position said buck member in work-receiving position when said intermediate members are in pressing engagement with said head member, and means for exerting pressure between said head member and said intermediate buck member and between said intermediate head member and said buck member.
28. A pressing machine comprising, in combination, frame means comprising a plurality of spaced supporting elements, a lower buck supported by and positioned between said elements, an upper head supported by and positioned between said elements, intermediate buck and head elements positioned between said frame elements, means for moving said intermediate elements between a position in pressing engagement with said head and a position in pressing engagement with said buck, means for exerting pressure between said head and said intermediate buck, means for exerting pressure between said intermediate head and said lower buck, and means to maintain said intermediate buck and said intermediate head in spaced relation throughout the operation of the device, whereby there is provided between said elements a recess for the reception of work.
